WILLIAM J. LILLY, OF BUTTE, MONTANA.

HOISTING-ENGINE CONTROL.

1,153,124.

Specification of Letters Patent. Patented Sept. 7, 1915.

Application filed April 2, 1914. Serial No. 329,019.

To all whom it may concern:

Be it known that I, WILLIAM J. LILLY, a subject of the King of Great Britain, residing at Butte, in the county of Silverbow and 5 State of Montana, have invented certain new and useful Improvements in Hoisting-Engine Controls, of which the following is a specification.

My invention relates to the control of hoisting engines and parts associated therewith, my purpose being to prevent overspeeding of the hoisting mechanism carrying the skip or cage.

More particularly stated, my invention 10 comprehends improved mechanism, controllable by the speed of the hoisting mechanism, for shutting off the power of the hoisting engine and for applying the brake mechanism.

20 My invention further comprehends mechanism, controllable partly by the speed of the hoisting mechanism and partly by the relative positions assumed by various movable parts, for stopping the hoisting engine 25 and applying the brake mechanism in the event that the operator fails to check the speed of the hoisting mechanism when the skip or cage reaches the proximate end of its trip either upward or downward.

30 Reference is made to the accompanying drawings forming a part of this specification, and in which like letters indicate like parts.

Figure 1 is a side view, partly in elevation 35 and partly diagrammatic, showing my device used in connection with a hoisting engine and brake mechanism associated therewith. Fig. 1^a is a detail view, showing in perspective various parts of the weight-controlled tripping device for stopping the hoisting mechanism. Fig. 2 is a detail view, 40 partly in side elevation and partly in section, showing the speed-controlled mechanism for throwing the tripping device into action, and for indicating by appropriate 45 signals any danger due to overspeeding. Fig. 2^a is a detail of the alarm mechanism. Fig. 3 is a front elevation of the mechanism shown in Fig. 2.

50 The hoisting engine is shown at 4, the throttle valve at 5, the throttle mechanism at 6, and the throttle shaft at 7. Mounted rigidly upon this throttle shaft, is an arm 8. An actuating bar 9 is provided 55 at one of its ends with a link 10, the latter fitting slidably upon a pin 11 carried by the

arm 8. When the actuating bar 9 is moved obliquely downward in the general direction of its length, the throttle mechanism is actuated and the engine is stopped.

60 Various movable parts of the engine are shown at 12, and at 13 is a connecting rod for actuating the throttle mechanism independently of the actuating bar 9. A lever 14 is disposed adjacent a platform 15, serving as the engineer's stand, and the lever 14 is connected with the rod 13.

65 The brake drum, forming a part of the hoisting mechanism, is shown at 16. The brake shoes appear at 17, and connected with them are brake levers 18. The brake shoes are supported upon rocking arms 19, having the usual or any preferred form. Connected with the brake levers 18 are rods 20, which are also connected to a lever 21 70 which is journaled upon a pedestal 22. Pivotally connected to the lever 21 is a connecting rod 23, the latter being also connected by a pivot 24 with the sliding head of a 75 brake engine 25. This brake engine may be substantially of the usual or any desired construction.

75 The brake drum 16 is provided with gearing 26, the latter being connected with a revolvable shaft 27, this shaft being connected by gearing 28 with a counter shaft 29. Mounted rigidly upon this counter shaft is a bevel pinion 30, which meshes with a bevel gear 31, as indicated in Fig. 1. The bevel gear 31 is mounted rigidly upon a 80 worm shaft 32, which carries a worm 33 and is journaled in bearings 34. A worm gear 35 meshes with the worm 33 and is driven slowly thereby. Mounted rigidly upon a shaft 29^a is a gear wheel 30^a meshing with 85 the gear 31 and upon the upper end of the said shaft is a gear wheel 36, which meshes with another gear wheel 37, the latter being mounted within a spider 38 constituting the upper portion of the frame work. Supported by this spider, is a sleeve 39. A centrifugal governor 40 is supported by the spider 38 and sleeve 39, and is provided with 90 a governor rod 41, slidably mounted and adapted to play vertically. The spider 38 is supported by frame work 42, the latter being provided with a cylindrical bearing 43. Extending through this bearing and loose relatively to the same is a sleeve 44 95 which serves the purpose of a hollow shaft. Encircling this hollow shaft and loose relatively to the same, is a spider 45 provided

with spokes 45^a and with a hub portion 45^b, these parts having together the proximate form of a large wheel, as may be understood from Figs. 2 and 3.

5 The worm wheel 35 is secured rigidly upon one end of a tubular shaft 46, which extends through the sleeve 44, and is loose relatively to the latter.

10 The spider 45 is provided with an annular rack 47 carrying rack teeth 48 extending radially inward. The spider 45 is further provided with a reduced annular portion 49, integral with it, and with the annular rack just mentioned, for the purpose of supporting the latter.

15 Fitted upon the annular rack 47 is a slide 50, provided with a number of notches 51 (see Fig. 3), these notches being disposed at different distances measured radially out-

20 ward from the axis of the annular rack 47. The slide 50 is further provided with a lug 52, integral with it, and with a set screw 53 for clamping the slide rigidly upon the annular rack. By loosening the set screw 25 53, the slide 50 may be moved relatively to the annular rack 47, and when thus moved may be secured in position by tightening the set screw. The slide 50 is thus adjustable relatively to the annular rack.

30 Another slide 54, somewhat similar to the one just mentioned, is provided with a set screw 55, notches 56, and a lug 57. This slide is adjustable relatively to the annular rack 47, but its notches 56 are upon the opposite side of the lug 57 as compared with the position of the notches 51 relatively to the lug 52.

35 Extending entirely through the tubular shaft 46 is a rod 58, the outer end of this rod being connected by a bearing 59 to an arm 60, this arm being journaled upon a pin 61. Integral with the arm 60 is another arm 62, these two arms together forming a bellcrank lever. Connected with this bellcrank lever is a pawl carrier 63, having the form of a slide, and mounted within a hollow arm 64. The pawl carrier 63 is adapted to be moved radially inward or outward. The hollow arm 64 carries a bearing 64^a 45 which supports the pin 61 and the bellcrank lever just mentioned.

40 A pawl 65, having in this instance the form of a trident head, is by aid of a pivot pin 66 mounted upon the upper end of the pawl carrier 63, and has a slight rocking movement relatively to said pawl carrier.

45 The rod 58 is connected by a bearing 67 (see Fig. 2) with the lower end of a bellcrank lever 68, this lever having an arm 69 50 extending horizontally. Pivoted connected with the arm 69 is a link 70. This link is also pivotally connected to a pin 70^a carried by the governor rod 41. A weighted lever 72 mounted upon a pin 71 extends 55 into engagement with the lower end of the

governor rod 41, and is movable by the vertical movements of this governor rod. The bellcrank lever 68 is supported upon a shaft 73, journaled in the frame work. Secured rigidly upon the shaft 73 and extending upwardly therefrom is an arm 74, provided with a number of holes 75. An actuating bar 76 is connected with the arm 74, and is adjustable by aid of the holes 75. The actuating bar 76 is provided with an adjustable link 77, which may be secured in two positions relatively to a pin 77^a. The bar 76 is operated by hand, for the purpose of actuating the arm 74, and of leaving the latter in either of two normal positions. At 80 78 and 79 are shown various levers and other movable parts, connected with the hand levers 14 and 14^a, and therefore under control of the engineer.

85 The weight 80, under control of the brake engine, is connected with the main brake lever 21 for the purpose of actuating the latter, and thus setting the brake.

90 Journaled within a pedestal 83 is a shaft 82 (see Fig. 1^a) carrying an arm 81, mounted rigidly upon it and pivotally connected with the actuating bar 9. The shaft 82 also carries an arm 84, secured rigidly upon it. Pivotally connected with the arm 84, and movable by it, is a rod 85, for controlling the brake engine and causing the brake mechanism to be set.

95 Mounted rigidly upon the shaft 82 is an arm 86, and this arm carries a weight 87 for turning the shaft 82. The arm 86 is 100 connected with a dashpot 86^a, for preventing unduly rapid or jerky movements of the arm 86 and shaft 82. Pivotally mounted adjacent the outer or free end of the arm 86 105 is a lever 88, which is engaged by the arm 86.

110 A bellcrank lever 89, serving the purpose of a trigger, is provided with a lug 89^a, which engages an adjacent portion of the lever 88, as indicated in Fig. 1^a. By bringing the parts 88 and 89 into the relation indicated in Fig. 1^a, the lug 89^a restrains the lever 88, and the latter supports the arm 86 carrying the weight 87. If, however, the bellcrank lever 89 is turned slightly in either of two directions, the lever 88 is released and disengages the arm 86, whereupon this arm swings downwardly under action of the weight 87. The shaft 82 is thus rocked, the arm 84 and rod 85 are moved downwardly, and the brake mechanism is thus set.

115 In order to actuate the bellcrank lever 89, I connect a rod 90 with it, as indicated in Fig. 1. The upper end of this rod is pivotally connected to another bellcrank lever 91, which at its top carries a U-shaped bearing 92. The annular rack 47 carries a pin 93 which extends into this bearing, and allows the annular rack to have a slight rocking movement, but not to rotate to any considerable extent.

The alarm mechanism is shown at the left of Fig. 2 and in Fig. 2^a. A contact 94 controls an electric bell 95, and is connected therewith by wiring 96. The contact 94 is in alinement with the rod 58, and so positioned that when this rod moves to the left, according to Fig. 2, the contact is closed and the bell 65 energized accordingly.

Another contact 97 is in communication with the bell 95. The worm 35 carries a spring 98, which is adapted to engage the contact 97 (see Fig. 2^a) and close the same, so as to complete a circuit through the bell 95.

15 The spring 98 is carried by a post 99 extending outwardly from the adjacent face of the worm wheel 35. These parts are so arranged that when the worm wheel, in turning, reaches one of the limits of its 20 travel, it causes the spring 98 to close the contact 97 and thus ring the bell.

The gearing for turning the worm wheel and parts driven thereby is so arranged that the travel of the worm wheel is very slow, 25 the entire range of travel of the worm wheel being less than one complete revolution. Such being the case, the arm 64 and pawl carrier 63, together with the pawl 65, always turn less than one complete revolution in 30 either direction—the limited amount of rotation which these parts undergo representing the aggregate amount of travel of the skip or cage, or in other words, corresponding to the maximum number of strokes ever 35 made in either direction by the hoisting engine.

The parts are so arranged that when the hoisting engine runs in one direction, so as to lower the skip or cage, the arm 64, pawl 40 carrier 63, and pawl 65, rotate in a counter-clockwise direction according to Fig. 3. When, however, the skip or cage is being raised, the arm, pawl carrier and pawl in question rotate in a clockwise direction according to this figure.

The operation of my device is as follows: The parts being assembled and arranged as described, the engineer starts up the hoisting engine to raise or lower the load, 50 consisting, say, of a skip or cage. If the load is to be lowered, the movement of the various revolute parts is such that the pawl 65 turns in a contra-clockwise direction according to Fig. 3, as above stated. Because of this fact, the pawl 65, in moving around, tends to come into engagement with some of the notches 56—provided the speed is not slackened. When the engine is running at full speed, the pawl 65 will enter the notches 56, but if the speed of the engine be slackened, the pawl will escape the notches. If, therefore, as the load nears the lower end of its journey, the engineer causes the speed of the hoisting engine to decrease, 60 the governor 40, by actuating the various

parts controllable by the governor rod 41, causes the pawl to be gradually drawn radially inward, and to thus miss the notches 56. The excessive speed being thus taken care of, the pawl will still engage the lug 57, 70 unless the engine is stopped completely by the time the load reaches its destination. Unless the engineer stops the engine as just mentioned, the pawl, by engaging the lug 57 or the notches 56, presses upon the slide 75 54 and rocks the annular rack 47 slightly in a contra-clockwise direction, according to Fig. 3. This actuates the bellcrank lever 91, causes the rod 90 to be thrust downwardly, and this rocks the bellcrank lever 89. The 80 lever 88 being thus disengaged, releases the arm 86, and the weight 87 thereupon drops. This rocks the shaft 82, pulls the rod 86 downwardly, and causes the throttle mechanism of the engine to be actuated so as to 85 cut off the power. It also causes the brake to be set.

Where the load is being raised instead of lowered, the action is quite similar to that just described, except that the various revolute parts move in the opposite direction, and the pawl 65 is brought against the notches 51 or lug 52 of the slide 50, instead of against corresponding parts of the slide 54.

In the event of the engine overspeeding, 95 either in hoisting or lowering the load, the rod 58 moves to the left according to Fig. 2, and causes a contact to be made at 94, which rings an alarm for overspeeding. If, now, the engineer fails to slacken the speed of 100 the engine, the action of the governor mechanism thrusts the pawl 65 into the teeth 48, which causes the rack 47 to turn. This shuts off the power and sets the brake, thus stopping the engine.

As the skip, in being raised, nears the surface of the earth, the contact spring 98 (see Fig. 2^a) is brought into engagement with the contact spring 97, thus completing a circuit and causing the bell to ring. The engineer is thus warned to slow down the engine so to prevent the pawl 65 from engaging with the teeth 51 and the slide 50, and thus having the control mechanism stop the engine.

When the skip or cage is intermediate its extreme positions, if at any time the speed of the engine becomes excessive, the speed governor mechanism is actuated, rod 58 is thrust against the button which closes 110 the contact at 94, and rings the bell for overspeeding, and the pawl 65 is moved radially outward and into engagement with the annular rack 47, the latter being thereby turned slightly, and caused to actuate the various 120 movable parts controlled by it, so that the throttle is actuated and the power cut off, the brake being also set.

The parts are so proportioned and arranged that the engineer has an opportunity, 130

after receiving a warning signal from the bell, to check the speed of the engine or to shut off the power as may be. It is preferable that the signal be first given so that 5 the engineer may have a chance to heed it, and if he fails to do so, the mechanism will be brought automatically to a standstill.

I do not limit myself to the precise mechanism shown, as variations may be made 10 therein without departing from the spirit of my invention.

Having thus described my invention, what I claim as new and desire to secure by Letters Patent is as follows:

15 1. A device of the character described, comprising a frame, a spider supported thereby and free to rock, a rack carried by said spider, a stop mounted upon said rack, an arm supported by said frame and movable relatively to said rack, a pawl carried by said arm and adapted to engage said rack so as to actuate said spider, speed controlled mechanism for shifting said arm toward and from said rack, a prime mover 20 and mechanism connected with said spider and controllable by movements thereof for controlling said prime mover.

2. A device of the character described, comprising a hoisting drum, speed-governor mechanism connected therewith and controllable by the speed thereof, a revoluble shaft geared in operative relation to said drum and driven thereby, a radially movable arm carried by said revoluble shaft, 30 pawl mechanism connected with said speed-governor mechanism and movable thereby in the general direction of the length of said arm, a movable rack of annular form disposed adjacent the path of travel of said 35 pawl and so positioned as to be engaged by the latter when said hoisting drum is driven at excessive speed, and mechanism connected with said movable rack and actuated thereby for controlling motions of said 40 hoisting drum.

3. A device of the kind described, comprising a hoisting drum, speed-governor mechanism connected therewith and controllable by the speed thereof, a revoluble 50 shaft geared in operative relation to said drum, a radially movable arm carried by said shaft, a pawl carried by said arm, connections from said speed-controlled mechanism to said pawl for the purpose of moving said pawl toward and from the axis of rotation of said arm, a movable rack of annular form disposed adjacent the path of travel of said pawl and so positioned as to be engaged by said pawl when said speed-governor mechanism acquires a predetermined 55 excess of speed, and mechanism connected with said movable rack and actuated thereby for controlling movements of said drum.

60 4. A device of the kind described, com-

prising a hoisting drum, speed-governor mechanism connected therewith and controllable by the speed thereof, a revoluble shaft geared in operative relation to said drum, a radially movable arm carried by 70 said shaft, a pawl carried by said arm, connections from said speed-controlled mechanism to said pawl for the purpose of moving said pawl toward and from the axis of rotation of said arm, a movable spider provided with a circular member disposed adjacent the path of travel of said pawl, a stop adjustably mounted upon said circular member and provided with surfaces disposed adjacent the path of travel of said pawl, so as 75 to be engaged thereby when said speed-governor mechanism acquires a predetermined excess of speed, and mechanism connected with said circular member and controllable thereby for stopping said hoisting drum. 80

5. A device of the character described comprising an annular rack provided with teeth extending radially inward, stop members adjustably mounted upon said rack and provided with notches, a pawl to be engaged by said notches or by said teeth as the case may be, a revoluble arm in which said pawl is slidably mounted, a bellcrank lever carried by said revoluble arm and engaging said pawl for thrusting the latter into engagement with said teeth or with said notches, a connecting rod connected with said bellcrank lever, and speed-controlled governor mechanism connected with said connecting rod for actuating the same. 90

6. The combination of a frame, a revoluble sleeve extending therefrom, a spider mounted upon said sleeve and adapted to rotate, a revoluble arm disposed adjacent to said spider, pawl mechanism carried by said arm for turning said spider, a connecting rod for actuating said pawl mechanism, a bellcrank lever connected with said connecting rod, governor mechanism, and connections from said governor mechanism to said bellcrank lever. 100

7. In a device of the character described, the combination with the throttle of an engine of, a member mounted to rock, a governor, means controlled by the governor for 115 rocking said member when the engine is running at excess speed and also when the speed has been slackened, a weight operated lever mechanism connected with the throttle of the engine, and a trip operated by the rocking member for releasing the said lever mechanism. 120

8. In a device of the character described, an engine, a member mounted to rock, a brake mechanism, a governor, means controlled by the governor for rocking said member when the engine is running at excess speed and also when the speed has been slackened, a weight operated lever mechanism connected with the lever mechanism, 130

and a trip operated by the rocking member for releasing the said lever mechanism.

9. In a device of the character described, the combination with the throttle of an engine, and a brake mechanism, of a member mounted to rock, a governor, means controlled by the governor for rocking said member when the engine is running at excess speed and also when the speed has been slackened, a weight operated lever mechanism, means for connecting the lever mechanism with the throttle of the engine, means for connecting the lever mechanism with the brake mechanism, and a trip operated by the rocking member to release the lever mechanism.

10. In a device of the character described, a rack mounted to rock, a stop carried by the rack, a governor, and a pawl controlled by the governor for rocking said rack.

11. In a device of the character described, a rack mounted to rock, a stop carried by the rack, a pawl for engaging the rack for rocking the same, a governor, a sliding member operated by the governor, and means operated by the sliding member for moving the pawl in and out of engagement with the rack.

12. In a device of the character described, a rack mounted to rock, a stop carried by the rack, a sliding pawl for engaging the rack to rock the same, a governor, a sliding member, means for operating the sliding member from the governor, and a bell crank

lever engaging the pawl and operated by the sliding member.

13. In a device of the character described, a member mounted to rock, a stop carried by the member, a governor, and a movable member controlled by the governor and adapted to engage the stop of the rocking member to rock said member.

14. In a device of the character described, a member mounted to rock, a stop carried by the member and having a plurality of surfaces projecting different distances from said member, a governor, a movable member, and means controlled by the governor for moving said member into the path of different surfaces of the stop to rock said member according to the speed of the engine.

15. In a device of the character described, a circular member mounted to rock, a stop carried by the member and having a plurality of surfaces projecting different distances from said member, a member mounted to turn and slide, and means controlled by the governor for moving said member into the path of different surfaces of the stop according to the speed of the engine.

In testimony whereof I have signed my name to this specification in the presence of two subscribing witnesses.

WILLIAM J. LILLY.
